CANNULA BUTTON FOR SURGICAL OPERATIONS AND METHOD OF USE

Charles F. Schnee, Maspeth, N. Y.

Application February 19, 1945, Serial No. 578,627

1 Claim. (Cl. 128—348)

2

This invention relates generally to surgical instruments and methods and more particularly to a cannula button for use in removing excess fluid from the abdomen in cases of ascites.

Devices and methods have heretofore been used for this purpose but these have not proven entirely satisfactory. Some of them were temporary expedients used at the time of the operation or at best for a period while the patient was hospitalized. In others, a connection was made between the abdomen and a vein in the thigh of the leg but such connection soon clogged up or became broken.

A primary object of the present invention is to overcome the above-mentioned defects and shortcomings of the present known devices and methods.

A further object is to provide a method and means for positively directing the excess liquid from the abdomen to a vein in the thigh, and so into the general circulation that it may be excreted through the kidneys.

Another object is to provide an improved device for forming a positive and rigid connection between the abdomen and a vein in the thigh.

Yet another object is to provide means for preventing the connection between the abdomen and the vein from becoming clogged up or broken.

Still another object is to provide means for facilitating fastening the abdominal wall and vein to the device.

A still further object is to provide such an instrument that is readily and easily mounted in position.

Another object is to provide an instrument of this kind that may remain permanently in the body without injury or deleterious results.

Another object is to provide such an instrument that is simple in construction and inexpensive to manufacture.

Further objects and advantages of the present invention will be apparent from the description thereof to follow taken in connection with the accompanying drawing in which—

Figure 1 is a sectional view of the human abdomen showing one form of my improved cannula button in position in the wall of the abdomen and connected to a vein.

Figure 2 is a side view of the improved cannula button shown in Figure 1, parts being shown in section.

Figure 3 is a front view thereof.

Figure 4 is a rear view thereof.

Figure 5 is a side view of a modified form of cannula button.

The improved instrument is in the form of a cannula button 1 made of any suitable metal, a known metal alloy having the approximate composition of sixty-five percent (65%) cobalt, thirty percent (30%) chromium, and five percent (5%) molybdenum having been found in practice to be very satisfactory for this purpose, said alloy being non-corrosive and producing no reaction in living tissues when embedded therein. The form 10 of button shown in Figures 1 to 4, inclusive, comprises a disc member 2 with a central opening 3. Secured to the periphery of the disc in any suitable manner and extending outwardly from one face thereof is a dome-shaped guard member 4 which as shown is preferably a hollow hemisphere. This guard member has a solid wall portion 5 at its apex, the remainder of the wall being formed with a plurality of perforations 6. A tubular shank or stem 7 extends laterally from 15 the opposite face of the disc and has one end suitably fastened to the walls of the disc opening 3 and has its other free end 8 bent at right angles to the plane of the shank. A retaining bead or flange 9 may be formed on the outer free edge 20 of the angular end 8.

The disc is provided with a number of openings 10 adjacent the periphery and a number of radially disposed eyelet members 11 adjacent its central opening, three of such openings and eyelet 25 members being shown, but any desired number may be provided.

The technique for using the improved cannula button is as follows:

An incision is made in the abdominal wall 35 18—12 into the peritoneal cavity 13 sufficiently large to permit the disc and dome-shaped guard member to be inserted into said cavity. The disc is then fastened to the wall by sutures 14 passing through the openings 10 in the disc. The peritoneal incision is then closed by suturing its margins over the disc 2, permitting shank 7 to pass 40 outward into the abdominal wall 17.

A vein in the thigh, such as the saphenous vein 15, having first been completely severed 45 across at a point below its connection to the femoral vein 16 and its severed portion suitably closed, is stretched or threaded through the abdominal wall 17 under the skin 18 upwardly to a point above the femoral vein and to a point 50 adjacent the incision in the abdominal wall. This stretched or reflected portion of the vein 15 is slipped or threaded over the tubular shank 7, for the entire length of said shank, and its end is then fastened to the eyelet members 11 by means 55 of sutures 19.

The fluid in the peritoneal cavity will pass through the perforations in the dome-shaped guard into the tubular shank and saphenous vein 15, finding an outlet in the femoral vein 16. The solid portion of the wall of said guard will guard off internal organs from coming up against the openings in the button.

In Figure 5 I have shown a modified form of cannula button in which the tubular shank 20 is arcuate-shaped instead of angular as shown in Figures 1 and 2. This shape facilitates threading of the vein 15 on to the shank. The shank 20 may also be longer than the shank 7 thereby making provision for abdominal walls of varying thickness.

It will be seen from the foregoing that I have invented a new method and instrument for removing excess fluid which accumulates in the abdomen of patients suffering with various types of liver disease, or mechanical obstruction to the portal venous system, which accumulation is commonly known as ascites.

Changes in details of construction might be resorted to without departing from the scope or principle of the invention and I desire to be limited only by the appended claim.

What I claim is:

A device of the kind described comprising a tubular member having a passage therethrough, a disc rigidly secured to one end of said tubular

member, said disc having a central opening communicating with the passage in the tubular member, and a dome-shaped guard member secured to said disc, said guard member having perforations communicating with the openings in the disc and tubular member, said disc having openings adjacent its periphery for suturing the abdominal wall thereto, and said disc also having eyelet members adapted for fastening a vein of the human body to the disc.
